Primary Examiner — Sheryl Lane*Assistant Examiner* — Nicole Shiflet*(74) Attorney, Agent, or Firm* — Design IP(57) **CLAIM**

The ornamental design for a display screen or portion thereof with graphical user interface, as shown and described.

DESCRIPTION

FIG. 1 is a front view of an image of a first embodiment of a display screen or portion thereof with graphical user interface showing our new design; and,

FIG. 2 is a front view of an image of a second embodiment of a display screen or portion thereof with graphical user interface showing our new design.

The broken line showing of a portion of a display screen in FIGS. 1 and 2 forms no part of the claimed design. The broken line showing of text and portions of the graphical user interface in FIGS. 1 and 2 represents environmental subject matter and forms no part of the claimed design.

1 Claim, 2 Drawing SheetsFIG. 1

FIG. 2
